UNITED STATES PATENT OFFICE.

FRED WALTHER, OF OMAHA, NEBRASKA.

COLLAPSIBLE POULTRY-CRATE.

1,303,746.

Specification of Letters Patent. Patented May 13, 1919.

Application filed May 14, 1917. Serial No. 168,426.

To all whom it may concern:

Be it known that I, FRED WALTHER, a citizen of the United States, residing at Omaha, in the county of Douglas and State of Nebraska, have invented new and useful Improvements in Collapsible Poultry-Crates, of which the following is a specification.

My present invention pertains to crates constructed with a view to being reduced in compass and returned in an empty state to the point from which they are shipped; and it consists in the peculiar and advantageous crate adapted to be expeditiously and easily collapsed and as readily set up ready for use as hereinafter described and definitely claimed.

In the accompanying drawings:

Figure 1 is a side elevation, showing a crate constructed in accordance with my invention as set up ready for use.

Fig. 2 is a horizontal section taken in the plane indicated by the line 2—2 of Fig. 1, with the walls 5 omitted.

Fig. 3 is a longitudinal vertical section showing the crate as collapsed.

Fig. 4 is an end elevation showing the crate opened or set up and ready for use.

Fig. 5 is an intermediate cross-section of same, with the walls 5 omitted.

Fig. 6 is a cross-section showing the crate collapsed.

Similar numerals of reference designate corresponding parts in all of the views of the drawings.

The specific construction herein disclosed constitutes the best practical embodiment of my invention that I have as yet devised, and I would have it understood at this point that either wood or metal may be employed to form the major portion of the crate.

Among other elements the crate comprises a bottom wall 1, flanged as indicated by 2 adjacent to its side edges, and flanged as indicated by 2^a adjacent to its end edges; the flanges 2^a extending the full width of the bottom wall and having their inner sides spaced from the ends of the flanges 2 for an important purpose hereinafter set forth. The crate also comprises a top wall 3 having side flanges 4 corresponding to the flanges 2 and also having end flanges 4^a corresponding to the end flanges 2^a of the bottom wall

and arranged with their inner sides spaced from the ends of the side flanges 4.

Interposed between the bottom wall 1 and the top wall 3 are inwardly folding side walls which respectively comprise lower and upper sections 5, hinged together at 6, to permit of the inward folding, as shown in Fig. 3, and hinged at their lower and upper edges to the inner sides of the side flanges 2 and 4 as shown. The said side walls correspond in length to the flanges 2 and 4, and hence their ends are spaced from the inner sides of the end flanges 2^a and 4^a. 55 60 65

At 7 is provided a transverse partition which for the sake of lightness is preferably of open-work construction as shown in Fig. 5. The said partition 7 is hinged at 8 to the bottom wall 1 and hence has the capacity of being swung from the position shown in Fig. 3 to that shown in Fig. 5 and vice versa. Adjacent to its free edge the partition 7 is provided with a suitable fastener 9, designed to be manipulated by an attendant into and out of engagement with a keeper 9^a on the underside of the top wall 3, the connection being effected when it is desired to maintain the partition 7 in an upright position and the crate in an open state, 70 75 80 and being interrupted when it is desired to swing the partition 7 into the position shown in Fig. 3 preceding the collapsing of the crate. For the purpose of manipulating the fastener 9 from a point exterior of the crate 85 access may be gained to the fastener through any available opening in one of the crate walls and in any approved manner.

Arranged in vertical planes immediately inside the vertical planes of the flanges 2^a and 4^a are collapsible end walls made up of lazytong members 10, riveted together and to the flanges 2^a and 4^a in a pivotal manner and adapted to be collapsed in closely arranged superimposed relation, after the manner shown in Figs. 3 and 6 and also adapted to be extended as shown in Fig. 4. It will here be noted that the vertically collapsible end walls are arranged in the same planes as the before referred to spaces between the inner sides of the end flanges 2^a and 4^a and the ends of the side flanges 2 and 4, and hence the said spaces are made to receive and accommodate the lazytong 90 95 100

members so that the crate may be collapsed to such an extent that the flanges of the top wall will rest in superimposed relation on the flanges of the bottom wall, with the 5 folded side walls and the collapsed end walls within said flanges, and the crate as a whole reduced to a very small compass, as shown in Fig. 3.

In the practical use of my novel crate, it 10 is secured in the open state shown in Figs. 1 and 4 by the described fastening of the partition wall 7 in upright position, and in such open state the crate is adapted for use after the manner of an ordinary crate. 15 When, however, the crate is discharged of its contents through doors (not shown), it is simply necessary for an attendant to reach inside the crate and detach the fastener 9 from the complementary keeper 9^a 20 on the top wall 3, and swing the partition 7 to the position shown in Fig. 3, whereupon the crate may be reduced to a collapsed state of small compass by pressing downwardly on the top wall 3 or by pressing the bottom 25 and top walls 1 and 3 toward each other, and in the collapsed state the crate may be conveniently returned to the point from which it was shipped with poultry or other produce.

30 In addition to the practical advantages hereinbefore ascribed to my novel crate, it will be appreciated that the crate is simple, cheap and so constructed that the flanges of the top and bottom walls meet when the 35 crate is collapsed, with the result that the side walls and the end walls are adequately protected during return shipment, and at the same time the crate is reduced to very small compass—i. e., about one third of the 40 full size when the major portion of the crate is of wood, and about one fourth of the full size when the major portion is of sheet-metal. Again the crate is well adapted to withstand the rough usage to which de- 45 vices of corresponding character are ordinarily subjected, and is further advantageous because it involves nothing in its construction that is calculated to detract from its capacity when it is set up ready 50 for use.

I have entered into a detailed description of the construction and relative arrangements of parts comprised in the present and preferred embodiment of my invention in 55 order to impart a full, clear and exact understanding of the same. I do not desire, however, to be understood as confined myself to the said specific construction and relative arrangement of parts inasmuch as such 60 changes in the form and arrangements of parts may be made in the future practice of the invention as are comprehended by the appended claims.

Having described my invention, what I claim and desire to secure by Letters Patent 65 is:

1. A collapsible crate comprising a bottom wall, a top wall, opposed walls interposed between the bottom wall and the top wall and each made up of sections hinged 70 together to fold inwardly and hinged to the bottom and top walls to swing thereon, and other opposed walls disposed at right angles to the said interposed walls and interposed between the bottom wall and the 75 top wall; the second named interposed walls being formed of lazytong members pivotally connected together and to the bottom and top walls.

2. A collapsible crate comprising bottom and top walls, each of said walls having end flanges on its inner side extending throughout its width and also having side flanges on its inner side and arranged with their ends spaced from the inner sides of 85 the end flanges, and the flanges of the said walls being arranged to meet when the crate is collapsed, opposed side walls interposed between the bottom and top walls and each made up of sections hinged together and to 90 inner sides of the side flanges and corresponding in length to said side flanges, and end walls interposed between the bottom and top walls and pivoted to the inner sides of 95 the end flanges and made up of lazytong members, pivotally connected together.

3. A collapsible crate comprising bottom and top walls, each of said walls having end flanges on its inner side extending throughout its width and also having side 100 flanges on its inner side and arranged with their ends spaced from the inner sides of the end flanges, and the flanges of the said walls being arranged to meet when the crate is collapsed, opposite side walls interposed 105 between the bottom and top walls and each made up of sections hinged together and to the inner sides of the side flanges and corresponding in length to said side flanges, end 110 walls interposed between the bottom and top walls and pivoted to the inner sides of the end flanges and made up of lazytong members pivotally connected together, a partition hinged on the upper side of the bottom wall and adapted to be swung to and from 115 an upright position, and co-operating means on said partition and the top wall for detachably connecting the former in upright position to the latter.

In testimony whereof I have hereunto set 120 my hand in presence of two subscribing witnesses.

FRED WALTHER.
